UNITED STATES PATENT OFFICE.

CARL S. HAMERSLEY, OF NEW YORK, N. Y., ASSIGNOR TO THE HAMERSLEY MANUFACTURING COMPANY, OF NEW YORK, N. Y., A CORPORATION OF NEW JERSEY.

PACKAGE.

Application filed April 8, 1922. Serial No. 550,855.

To all whom it may concern:

Be it known that I, CARL S. HAMERSLEY, a citizen of the United States, residing at New York city, in the county of New York and State of New York, have invented new and useful Improvements in Packages, of which the following is a specification.

My invention relates to an improvement in packages for supplying materials such as waxed paper for example in an inexpensive sanitary and convenient form whereby contamination of the material will be in a great measure avoided and whereby the supply of the paper or other material will be conserved.

A further object of the invention is the provision of an improved package from which the paper or other material forming a part thereof may be easily removed as required and only as much material as may be required at the moment need be removed.

A further object of the invention is the provision of an improved receptacle for the paper or other material whereby the supply of paper may be easily replenished from time to time.

Hereinafter in order that my invention may be clearly understood I will describe the same in connection with waxed paper, but it is to be understood that this use is merely illustrative and not in any sense definitive.

In carrying out the invention I preferably supply the waxed paper in roll form which I insert in a container or receptacle of suitable dimensions for the purpose but preferably of such a length that the ends of the roll of paper or the tube on which it is rolled will engage the ends of the inside of the container. The box or container may be made of pasteboard for example or other inexpensive material but preferably of a material which is more or less flexible for a purpose to be herein-after pointed out. Passing from end to end of the box is a cord or wire, which is passed through the tube on which the paper is rolled or if no tube be employed through the center of the roll and longitudinally thereof. One end of this cord or wire is preferably secured to one end of the box the other end of the cord passing through the other end of the box and projecting therefrom for some distance.

For convenience this end of the cord which I will refer to as the free end is provided with a small weight. In order that the paper may be kept clean and sanitary I provide a cover for the box.

In use the free end of the cutting or tearing cord is brought back over the roll of paper, the box cover having first been removed. The free edge of the paper is then drawn over the top of the cord and as much paper as desired drawn out of the box. By holding the free edge of the paper down with one hand the operator by grasping the free end of the cord and raising the same will draw the cord through the paper to sever a strip therefrom. In drawing the cord through the paper the cord is preferably placed under sufficient tension to flex the ends of the box against the ends of the paper roll which effectually prevents turning of the roll in the box during the cutting or severing operation. When the supply of paper becomes exhausted it is merely necessary to pull the free end of the cord through the end of the box and thread a new roll on the cord.

It is to be understood of course that this invention is not to be limited to the use of waxed paper nor necessarily to the use of paper in a roll form.

It is to be understood also that if desired the cutting or severing cord may extend the length of the box but once provided the roll of paper fits the box snugly enough to prevent turning. In that case I would fasten one end of the cord to the end of the box, and bring the free end back to the other end and proceed to sever a strip of paper as before.

In the accompanying drawing I have illustrated my invention in the form of a roll of waxed paper enclosed in a box, Figure 1, showing the apparatus in perspective and Figure 2 being a longitudinal section through the box and the roll of paper.

Referring to the drawings in detail 1 designates a box which may be of pasteboard for example, the walls 2 and 3 of the body portion thereof being preferably flexible for a purpose to be herein-after pointed out. Secured to the wall 2 in any suitable manner is a cutting or severing cord 4. This cord as will be seen from an in-

spection of Figure 2 passing longitudinally of the box and extends through the wall 3 a distance equal substantially to the length of the box. As will be seen from Figure 5 2 the cord 4 is bent back upon itself, its free end being provided with a weight 5. The paper designated 6 here illustrated is in the form of a roll mounted on the usual tube 7 the roll of paper on the tube being 10 substantially the length of the interior of the box 1. The cord 4 in passing from one wall to the other of the box is passed through the tube 7 on which the paper is mounted to prevent accidental removal of 15 the roll of paper from the box. The cord 4 in passing through the wall 3 passes through an opening 8 this opening being large enough preferably to permit of passage therethrough of the weight 5 heretofore referred to. I provide this construction in order that when the supply of paper 20 in the box is exhausted the cord 4 may be pulled through the opening 8, the empty tube 7 removed and a new roll of paper 25 threaded on the cord 4.

In order that the contents of the box may be kept clean I provide box cover 9 shown in place on the box in Figure 2.

When it is desired to cut or sever a section 30 of the paper from the roll it is merely necessary to remove the box cover 9 and then to grasp the edge 10 of the paper, withdrawing the desired amount of paper from the box, it being understood that in withdrawing 35 the paper it is drawn over the top of the cord 4. By placing the hand upon the withdrawn section of the paper as indicated in dotted lines in Figure 1 and by grasping the free end of the cord 4 in the other hand and raising the free end of the 40 cord as indicated in Figure 1, the desired amount of paper is severed or cut from the roll. The walls 2 and 3 of the box being flexible as above noted, they will be forced 45 into frictional engagement with the ends of the roll of material within the box during the cutting operation thereby frictionally holding the roll against rotation during this operation.

50 If desired the cord 4 may be fastened to the wall 3 of the box instead of to the wall 2 in which event it will not pass through the tube 7 at all. I prefer, however, the construction illustrated in the drawings in 55 that as pointed out above by passing the cord through the tube 7 accidental removal

of the roll of paper or other material from the box is effectually prevented.

It will be seen from the foregoing that I have provided a device whereby paper and other material may be supplied in an inexpensive, sanitary and convenient form and whereby the supply of paper or other material will be conserved. It will be seen also that by passing the cord through the 65 roll of paper and by securing one end of the cord to one wall of the box or container, not only is the roll held in the box but rotation of the roll during the cutting operation is prevented. 70

What I claim is:

1. In a device of the character described, the combination of a container, a roll of paper therein, a cord fastened to one end of the container and extending through the 75 paper roll longitudinally thereof and beyond the other end of the container a distance substantially not less than the length of the paper roll.

2. In a device of the character described, 80 the combination of a container, a cord attached to one end thereof, the other end of the container being provided with an opening through which the free end of the cord is passed, a weight carried by the free end 85 of the cord, said cord extending beyond the end of the container a distance substantially equal to the length of the container.

3. In a device of the character described, 90 the combination of a container, a roll of paper therein, a cord fastened to one end of the container and extending through the paper roll longitudinally thereof and to and through the other end of the container, the cord extending beyond the end of the 95 container a distance substantially equal to the length of the paper roll.

4. In a device of the character described, the combination of a box, a roll of paper in 100 said box, a cord secured to one wall of the box and extending through the roll of paper longitudinally thereof and through the opposite wall, one of said walls being flexible whereby when the cord is reversely bent for the cutting or severing operation the ends 105 of the paper roll will be engaged by opposite walls of the box and held against rotation during the cutting or severing operation.

This specification signed this 6th day of 110 April, 1922.

CARL S. HAMERSLEY.
